UNITED STATES PATENT OFFICE.

NELLIE L. FAY, OF NEW YORK, N. Y., ASSIGNOR OF ONE-HALF TO LILLIAN E. SCOFIELD, OF NEW YORK, N. Y.

BRASSIÈRE.

1,420,248.

Specification of Letters Patent. Patented June 20, 1922.

Application filed January 22, 1920. Serial No. 353,153.

To all whom it may concern:

Be it known that I, NELLIE L. FAY, a citizen of the United States, and resident of the borough of Manhattan, city, county, and State of New York, have invented certain new and useful Improvements in Brassières, of which the following is a specification.

My invention relates to brassières and has for its object to provide an improved and novel garment of this type which by reason of its construction remains in proper position upon the wearer, particularly at the front, without the assistance of any shoulder straps or equivalent devices and which is comfortable to wear and efficient for its intended purposes. Other objects of my invention will appear from the description hereinafter and the features of novelty will be pointed out in the appended claims.

In the accompanying drawings which, for illustrative and descriptive purposes show a specific embodiment of the invention, Figures 1 and 2 are front and rear views of the brassière in position on the human figure; Fig. 3 is a face view of the brassière; Fig. 4 is a view of the brassière as it appears when worn; Fig. 5 is a section thereof on the line 5—5 of Fig. 1; and Figs. 6 and 7 are views similar to Figs. 3 and 4 showing my brassière in a form designed particularly for day wear or with ordinary clothing.

In constructing the brassière, I start with a piece of fabric of rectangular shape cut on the bias and fold it upon itself along the line 10 so as to produce a double layer of fabric in which the weave of the one layer runs on the bias in one direction as indicated at 11 and the weave of the other layer runs on the bias transversely across the first in the opposite direction as shown at 12. With this arrangement the strains and stresses to which the garment is subjected when worn are neutralized with the result that the original shape of the finished garment is not materially changed by wear while at the same time the efficiency of the garment as a medium for supporting the figure is increased to a maximum degree.

After having been folded upon itself as described, the two opposed free edges of the fabric which run parallel with the fold 10 are sewed together as indicated at 13 after which the opposite ends of the fabric are taken in or reduced by means of darts 14 which are located in the two layers of fabric independently of each other and run in the

general direction of the length of the garment. This arrangement of darts 14 whereby the end portions of the fabric are reduced in width changes the fold 19 which forms the upper edge of the brassière, from an approximately straight line to one which is curved, as shown in Figs. 3 and 6, and which follows the natural contour of the figure, said darts also decreasing the length of the lower edge to a dimension in harmony with the figure for which the particular brassière is intended. In the construction shown in Figs. 3, 4 and 5, a second row of stitches 15 running parallel with the stitches 13 may extend lengthwise of the brassière to form a pocket along its lower edge in which an elastic tape 16 is contained whereby the garment automatically adjusts itself to different waist sizes, the tape being secured only at its ends to the garment. Any suitable means may be provided for securing the brassière upon the wearer; for instance, the opposite ends thereof may be finished off with fabric sections 17 attached by stitching 18 and provided at their free edges with co-operating fastening devices 19 and 20, for instance such as hooks and eyes.

The form of brassière shown in Figs. 1 to 5 inclusive is intended primarily to be worn with evening clothes although it loses none of its inherent advantages when worn with ordinary clothes. When designed specially for day wear or with ordinary garments the brassière may be made in the form shown in Figs. 6 and 7, which differs from the form illustrated in Figs. 1 to 5 only in the fact that it is constructed with a higher back. In other words, the end sections 17 of the form first described are replaced by fabric end sections 17^a which are formed with curved upper edges 21 and may be boned as indicated at 22, said sections 17^a being also somewhat wider than the sections 17. Because of this higher back arrangement it may be desirable to provide shoulder straps 23 of any suitable type which are fastened to said sections 17^a and also to the front portion of the brassière. These straps 23 prevent the higher back sections 17^a from falling down or folding over because of the movements of the wearer and perform no function in supporting the front portion of the brassière which is self-sustaining upon the wearer as in the form first described. In all other respects both forms may be alike, the elastic tape 16 being omitted in Figs. 6

and 7 to illustrate a garment in which the same is not required and in which the bottom edge is cut to fit a form of certain dimensions. Supporting devices 24 of the type generally found in brassières may be included in the present garment if desired.

In its finished condition, the brassière consists of a section of fabric cut on the bias and preferably comprising two layers 10 in which the weave extends on the bias in directions transverse to each other. The introduction of the darts 14 serves to so shape the garment that it snugly fits the figure of the wearer and closely follows the 15 contour thereof without the necessity for any seams running in vertical directions in the main portion of the garment. The result of this is that the brassière supports itself in position upon the wearer and requires no shoulder straps or equivalent devices to maintain it in position, particularly at the front, so that said brassière is 20 specially adapted for wear with evening clothes as shown in Figs. 1 to 5 inclusive and presents the same advantages when 25 designed for day wear or for wear with ordinary clothes. When made of a double layer of fabric, the two layers preferably have no connection with each other excepting 30 at their opposite edges and opposite ends and the darts in one layer are entirely independent of those in the other layer. This provides a freedom of movement and adjustment which insures at all times a maximum of efficiency.

The brassière may be made of madras, silk or any other suitable material and is simple in construction and economical to produce and provides a brassière which is 40 specially adapted for wear with evening gowns and the like.

Various changes in the specific form shown and described may be made within the scope of the claims without departing 45 from the spirit of my invention.

I claim:

1. A brassière comprising opposite end sections, an intermediate fabric section connected with said end sections and consisting 50 of two complemental layers in which the weave extends on the bias in directions

transverse to each other in the respective layers, and means carried by said end sections for fastening the brassière in place.

2. A brassière comprising a fabric section 55 consisting of two complemental layers in which the weave extends on the bias in directions transverse to each other in the respective layers, darts extending inwardly from the opposite ends of said section 60 whereby said ends are reduced in width and the upper edge of the section is curved from an intermediate point toward its opposite ends and means whereby the ends of said section are detachably connected. 65

3. A brassière comprising a fabric section cut on the bias and folded upon itself to form the upper edge of the garment and to provide two complemental layers in which the weave extends on the bias respectively in directions transverse to each other, stitching whereby the opposed free lower edges of said layers are permanently connected, darts located in each layer independently of each other and extending 75 inwardly from the opposite ends of said section whereby said ends are reduced in width and said upper edge is curved from an intermediate point toward its opposite ends and means whereby the ends of said 80 section are detachably connected.

4. A brassière comprising a fabric section cut on the bias and folded upon itself to form the upper edge of the garment and to provide two complemental layers in 85 which the weave extends on the bias respectively in directions transverse to each other, stitching whereby the opposed free lower edges of said layers are permanently connected, darts extending inwardly from the 90 opposite ends of said section whereby said ends are reduced in width and said upper edge is curved from an intermediate point toward its opposite ends, an elastic tape extending along the lower edge of said section 95 whereby said lower edge is automatically fitted to waist measurements and means for detachably connecting the ends of said section.

In testimony whereof I have hereunto 100 set my hand.

NELLIE L. FAY.
